UNITED STATES PATENT OFFICE.

IRVIN RITTENHOUSE, OF WASHINGTON, DISTRICT OF COLUMBIA, ASSIGNOR TO HORACE F. CLARK, OF WASHINGTON, DISTRICT OF COLUMBIA.

PAPER-FASTENER.

1,233,912.

Specification of Letters Patent. Patented July 17, 1917.

Original application filed March 10, 1910, Serial No. 548,339. Divided and this application filed April 28, 1913. Serial No. 764,168.

To all whom it may concern:

Be it known that I, IRVIN RITTENHOUSE, a citizen of the United States, residing at Washington, in the District of Columbia, 5 have invented new and useful Improvements in Paper-Fasteners, of which the following is a specification.

This invention relates to improvements in paper fasteners and more particularly 10 to that type of paper fasteners described in my co-pending application, Serial No. 548,339, filed March 10, 1910, of which this application is a division.

The object of this invention is to provide 15 a fastener consisting of a base member, a pliable fastening strip operatively associated with said base member, and a protecting plate coöperating with said pliable fastening strip.

20 A particular object of this invention is to provide a base member of such a character that a substantially flat surface will be presented to the bottom sheet of the plurality of papers desired to be secured by the fastener. One disadvantage of the former base member shown and described in my Patent Number 920,393, lies in the fact that a continuous binding surface is not presented to the lowermost sheet of the papers secured 25 by the fastener, so that there is a liability of any one or a number of the papers becoming loosened from the fastener, thereby destroying the binding of the file. The purpose of this invention is to obviate this difficulty 30 and at the same time, provide a simple and efficient means for retaining the fastening strip in operative association with the base member and also to provide means for properly guiding the fastening strip into correct 35 alinement with the base member during the operation of its insertion into the base member as will be hereinafter more fully described.

To this and other ends the invention consists in the construction, arrangement and combination of parts which will be herein-after more fully described in a preferred form, reference now being had to the accompanying drawing, in which:

40 Figure 1 is a top plan view of the base member showing the fastening strip in operative association therewith;

Fig. 2 is a bottom plan view of the base member to illustrate the means for retaining

the fastening strip in its operative position 55 on the said member;

Fig. 3 is a section on the line 3—3 of Fig. 2; and

Fig. 4 is a view partly in section showing the complete fastener securing a bundle of 60 papers.

As shown in the drawing, the base member 1 consists of an oblong strip of metal, having a plurality of punched-in portions 2, arranged on each side of its longitudinal 65 center line. These punched-in portions have their free ends 3 inclined inwardly toward the said longitudinal center line of the base member to provide a seat 4 on which rests the fastening strip 5 when in its operative 70 position on the base member. The fastening strip consists of an elongated member, preferably constructed of pliable metal, and of a length considerably greater than the base member 1, in order to provide extensions 6 and 7, which, when properly assembled, as hereinafter fully set forth, form a pair of prongs adapted to pierce the papers 75 desired to be secured by the fastener.

For the purpose of binding the plurality 80 of papers on the other side of the file, there is provided a protecting plate 8 having openings 9 and 10 spaced apart a distance substantially equal to the length of said base member, which openings are designed for 85 the reception of the extensions 6 and 7 of the base member 1. Between the inner edges of the openings 9 and 10 is a raised portion 11 which serves to strengthen the protecting plate and at the same time provides off-sets 90 at the points 9 and 10, whereby the extensions 6 and 7 may be properly guided into the respective pin receiving openings in the protecting plate. That portion of the said plate between the outer edge of the openings and the edge of the plate is beveled slightly, to provide a gripping surface for engagement with the papers at these points respectively. At the same time, a guide is formed, whereby the extensions 95 may be bent downward into intimate contact with the papers, and thus obviate the disadvantage of the prongs sticking up and mutilating contacting objects.

In operation, the fastening strip is inserted into the space between the under surface of the base member and the seat formed by the punched in portions 2 on each side of

the longitudinal center line of the base member, until the extensions 6 and 7 are equal in their respective distances from the opposite edges of the base member. These extensions are then bent upwardly over the base member until they are in substantially a vertical position. The papers are then arranged one by one over the fastener, the upstanding extensions forming means for 5 piercing the papers. If desired, however, the papers may be previously punched, in any suitable manner, in which case, it will only be necessary to insert the extensions into the openings in the papers. When the 10 number of papers has reached a height to complete the file, the extensions are passed into the openings 9 and 10, and the protecting plate, guided by the off-sets at these points, and the ends of the extensions are in 15 turn bent downwardly and outwardly over the beveled surfaces until they come into contact with the uppermost sheet of the file. 20 As will be noted, the advantage of this form of base member, lies in the fact that 25 with the exception of the punched-in portions, the entire flat surface of the base member is presented to the lowermost sheet of paper, thereby securing a perfect binding contact at every point on the base member. 30 Another advantage lies in the fact that the longitudinal punched-out portions form, in effect, strengthening ribs, thus greatly increasing the transverse tensile strength of the base member, and thereby greatly reducing 35 the danger of the base member becoming bent in a direction transverse to its longitudinal axis. By presenting a flat surface to the file, the disadvantage of a springing outward at the center of the base member, while 40 the free ends of the fastening strip are be-

ing bent back and forth during the operation of inserting additional sheets to the file or removing the same therefrom, is entirely obviated and the binding action of the base member upon the lowermost sheet is secured at all times. 45

What is claimed is:

1. A paper fastener comprising a base member having struck out parallel portions underlying the base and forming crotched 50 guideways, the struck out portions having their inner ends spaced from each other and their outer ends spaced from the ends of the base, and a pin fastener adapted to have one face bear flush against the end surface of 55 the base member when its side edges engage the crotches of the struck out portions, the pin fastener being arranged to engage the ends of the base member when bent up.

2. A paper fastener comprising a base 60 member having two sets of struck out parallel portions underlying the base and forming two crotched guideways, the struck out portions having their inner ends spaced a considerable distance from each other and 65 their outer ends spaced from the ends of the base, and a pin fastener formed of flat metal having its face bearing flush against the end surface of the base member and its lower face and edges engaging the struck 70 out portion and adapted to be bent upwardly and engage the ends of the base.

In testimony whereof I have hereunto set my hand in presence of two subscribing witnesses.

IRVIN RITTENHOUSE.
